STACY B. HASELTINE, OF CHICAGO, ILLINOIS, ASSIGNOR TO WILLIAM H. MINER, OF CHAZY, NEW YORK.

TANDEM SHOCK-ABSORBING MECHANISM.

1,355,967.

Specification of Letters Patent. Patented Oct. 19, 1920.

Application filed April 3, 1919. Serial No. 287,253.

To all whom it may concern:

Be it known that I, STACY B. HASELTINE, a citizen of the United States, residing at Chicago, in the county of Cook and State of Illinois, have invented a certain new and useful Improvement in Tandem Shock-Absorbing Mechanisms, of which the following is a full, clear, concise, and exact description, reference being had to the accompanying drawings; forming a part of this specification.

This invention relates to improvements in tandem shock absorbing mechanisms.

Since the railroads of the United States have been placed under the control of the United States Railroad Administration, certain standards have been adopted for all railroads and among others standards for the draft gears. Under the regulations of the Railroad Administration, cars must be built with a standard spacing of 24 $\frac{1}{2}$ " between front and rear sets of stops so that these stops will accommodate the ordinary friction gears now on the market. The spacing of 24 $\frac{1}{2}$ " is considerably shorter than that heretofore required by standard tandem spring gears and consequently the former types of tandem spring gears cannot be interchanged with the friction gears employed with the standard spacing of 24 $\frac{1}{2}$ ". There are numerous railroads in the United States which, prior to the passing of control to the Railroad Administration, had made spring gears standard and which object to the use of friction gears. These roads are still desirous of employing spring gears but obviously the same must be made so as to be interchangeable with the friction gears employed with the standard spacing of 24 $\frac{1}{2}$ " and they must also be employed without requiring any change in the single pocket yokes used with the friction gears.

The object of my invention is to provide a simple and inexpensive tandem gear arrangement of the spring type which may be interchanged with friction gears now made standard by the United States Administration, which spring gear will occupy the space of 24 $\frac{1}{2}$ " and be usable with a single pocket strap.

In the drawing forming a part of this specification, Figure 1 is a horizontal, sectional view of a portion of a railway draft rigging showing my improvements in con-

nexion therewith. Fig. 2 is a vertical, transverse, sectional view taken substantially on the line 2-2 of Fig. 1. And Fig. 3 is a detailed perspective of one of the follower members employed with my improvement.

In said drawing, 10-10 denote channel-shaped center or draft sills of a railway car to the inner faces of which are secured front lugs 11-11 and rear lugs 12-12 spaced 65 apart the present standard distance of 24 $\frac{1}{2}$ ". The draw bar is indicated at 13 and the same is operatively associated with the shock absorbing mechanism proper by a single pocket yoke strap 14. All of the movable parts are supported by a detachable saddle plate 15.

In carrying out my invention, I employ tandem springs 16-16 and two castings A-A. Each of the castings A is of substantially box form and has an outer end main wall 17 adapted to act as an end follower, as will be apparent from an inspection of Fig. 1. Each casting A also has a pair of longitudinally extending spaced 70 arms 18-18 connected at their inner ends by a transversely extending wall 19, the latter being provided with a narrow integral wall 20 forming an intermediate follower, as hereinafter explained. The main 75 end wall 17 corresponds in width and height to the usual follower and the side arms 18 for a part of their length correspond in height to the height of the end wall 17. Said arms 18, however, are narrowed at 80 their inner ends as indicated at 21 in Fig. 3 so that the narrowed portions 21 of one member A are adapted to overlap the corresponding narrowed portions of the other member A. The overlapping arrangement 85 of the arms is best shown in Fig. 2, the arms of one member being in section and the other in end elevation.

The narrowed follower sections 20 at the inner ends of the members A are made so 100 that they will readily fit between the longitudinally extending arms 18 of the other members as shown in Fig. 1. The members A are made counterparts and are assembled with one member in the position best indicated by Fig. 3 and the other member turned upside down and fitting thereover. As will be understood, each spring 16 is interposed between the main end wall 17 105 of one member A and the intermediate fol- 110

lower 20 of the other member A. With this arrangement, upon either inward or outward movement of the draw bar, one of the members A will be held stationary and the 5 other will move relatively toward it so that the springs will be compressed simultaneously, each between a main end wall of one member A and the intermediate follower section of the other member. To prevent 10 over-compression of the springs, shoulders 22 are formed on each member A in alignment with the inner ends of the arms of the other member A, the shoulders being so located as to be normally spaced from the 15 arms of the opposite member a distance corresponding to the permissible compression of the springs. It will be noted that upon full compression, an extremely rigid column of rectangular form is provided to absorb 20 the ultimate shocks.

As will be understood by those skilled in the art, the various parts of each member A will be substantially braced by ribs and flanges such as indicated, for instance, by 25 Fig. 3. It is not deemed necessary to enter into a detailed description of these strengthening flanges and ribs inasmuch as the same may be varied.

I claim:

30 1. In a tandem shock absorbing mechanism, the combination with two follower members, of two shock absorbing units, each of said members comprising a single casting having an outer end adapted to act 35 as an end follower, a pair of inwardly and longitudinally extending arms, and a narrow follower at the inner ends of said arms, the arms of said members partially overlapping and the narrower follower of each 40 member fitting between the arms of the other member, said narrow followers overlapping each other, each shock absorbing unit bearing solely on the narrow follower

of one member and the outer end of the other member.

2. In a tandem draft rigging, the combination with draft sills having front and rear sets of stops, a draw bar, and a single pocket yoke, of a pair of like follower members, and a pair of tandem arranged springs, 50 each of said follower members being of box-like form and having a main end wall, integrally spaced longitudinally extending arms, and an inner integral narrow follower, the arms of said members being partially overlapped and slideable relatively to each other, the narrow follower at the inner end of one member sliding between the arms of the other member, each spring bearing entirely upon the narrow follower of one 60 member and the main outer end of the other member.

3. In a tandem draft rigging, the combination with draft sills having front and rear stop-acting means, of a pair of castings, and tandem arranged springs, each of said castings being of substantially hollow box-like form and having a main transversely extending end wall, spaced longitudinally extending side arms, and an inner 70 wall, said side arms being of reduced height at their inner ends and, when assembled, the narrower portions of the side arms of one casting overlying the narrower portions of the arms of the other casting, the inner wall 75 of each casting being of reduced width for a part of its height and adapted to slide within the arms of the other casting, each spring being interposed between the inner wall of one casting and the main end wall 80 of the other casting.

In witness that I claim the foregoing I have hereunto subscribed my name this 28th day of March, 1919.

STACY B. HASELTINE.
